UNITED STATES PATENT OFFICE.

HERBERT C. SEGELKEN, OF PHOENICIA, NEW YORK.

PISTON-RING COMPRESSOR.

Application filed February 10, 1926. Serial No. 87,828.

This invention relates to piston-ring compressors, and has for its primary object to provide such a compressor that may be applied to a particular ring within a groove 5 of the piston and then released for permitting both hands of the mechanic to properly force the piston into the engine cylinders, the compressor automatically maintaining the ring in compressed condition after the same has been once applied.

A further object resides in the provision of such a compressor that may be easily applied to piston rings of various sizes and that may be used for the purpose intended 15 without requiring any unusual skill upon the part of the mechanic.

A still further object is the provision of a compressor of the type mentioned that is relatively simple in construction and inexpensive of manufacture, the invention comprising but few parts and these so correlated as to reduce the possibility of the disarrangement to a minimum.

With the foregoing and other objects in view as the nature of the invention will be better understood, the same comprises the novel form, combination, and arrangement of parts hereinafter more fully described, shown in the accompanying drawing, and 30 claimed.

In the drawing wherein like reference characters indicate corresponding parts throughout both of the views:

Fig. 1 is a longitudinal section of a piston-ring compressor constructed in accordance with the present invention, and

Fig. 2 is a side elevation thereof.

Now having particular reference to the drawing, my novel piston ring compressor 40 includes a cylindrical handle member 5 of wood or other substantial but inexpensive material open at one end and provided at its opposite closed end with a slot 6, the end walls of which are beveled as clearly shown in Fig. 1. The compressor further includes a relatively wide split spring steel ring 7 upon the ends of which are formed arms 8 of spring steel that converge inwardly toward each other as clearly shown in 45 Fig. 1, the same adapted to enter the slot 6 of the cylindrical handle 5, and from the ends of which arms extend relatively elongated horizontal bars 9 movable within the cylinder 5, the outer ends thereof extending 55 outwardly of the cylinder and being so bent as to provide outwardly extending finger

pieces 10 that will engage the adjacent end of the cylinder for preventing the withdrawal of the bars therefrom.

Surrounding said bars 9 between the finger pieces 10 and the forward end of the cylinder 5 is an expansible coil spring 11 that normally serves to draw the fingers 8 into the cylinder for consequently compressing the band 7, it being obvious that by 60 forcing the bars 9 upwardly or outwardly of the cylinder through the medium of the finger pieces 10 the band 7 will by reason of the material forming the same expand for 65 permitting a piston ring A to be disposed 70 therein.

It will be obvious that after the band 7 has been applied to a piston ring within a piston groove and then released, the spring 11 will automatically draw the bars 9 downwardly within the cylinder, which action 75 will move the arms 8 toward each other, consequently compressing the band upon the ring and in turn compressing the ring within the groove and flush with the piston wall 80 for permitting the piston to be moved downwardly within the engine cylinder, the positioning of the piston within the cylinder being performed by both hands of the mechanic by reason of the fact that the compressor will be automatically maintained in 85 proper position.

Minor changes may be made in the invention without departing from the spirit and scope of the appended claims.

Having thus described the invention, what I claim as new and desire to secure by Letters Patent is:—

1. In a compressor for piston rings, a cylindrical handle member, a split spring 95 steel band, rods upon the ends of the band slidable within said handle member, cooperating construction between the rods and said handle member for normally moving the band toward the handle and simultaneously compressing said band, and means at the opposite end of the handle whereby the band may be moved away from the handle and into expanded condition.

2. In a compressor for piston rings, a 105 normally expanded split steel band, a cylindrical handle member, rods extending from the ends of the band and entering said handle member, cooperating construction between the rods and said handle member 110 for drawing the rods through the handle member and simultaneously compressing

the band, and means at the opposite end of the rods externally of the handle whereby the same may be moved in a reverse direction to permit of the expansion of said band.

3. In a compressor for piston rings, a normally expanded split steel band, a cylindrical handle member, rods extending from the ends of the band through said handle, the free ends of said rods being disposed

laterally in opposite directions to provide finger pieces for drawing the rods through the handle member and simultaneously compressing the band, and an expansible coil spring arranged within the handle and enclosing said rods. 15

In testimony whereof I affix my signature.

HERBERT C. SEGELKEN.
